UNITED STATES PATENT OFFICE.

JOHN W. NUNAMAKER, OF CHICAGO, ILLINOIS.

CHRONOMETER-ESCAPEMENT.

SPECIFICATION forming part of Letters Patent No. 781,605, dated June 23, 1903.

Application filed February 9, 1903. Serial No. 142,552. (No model.)

To all whom it may concern:

Be it known that I, JOHN W. NUNAMAKER, a citizen of the United States, residing at Chicago, in the county of Cook and State of Illinois, have invented a new and useful Improvement in Chronometer-Escapements, of which the following is a specification.

My invention relates to improvements in chronometer-escapements wherein the balance-wheel receives its impulses directly from the teeth of the escape-wheel.

My object is to provide such an escapement of generally improved construction, possessing characteristics which render it particularly simple, strong, durable, and inexpensive to construct and free from all danger of unlocking the escape-wheel at the wrong time.

My object is further to dispense with the delicate auxiliary springs and parts usually provided in escapements of this class.

In the drawings, Figure 1 is a broken sectional plan view of so much of the escapement mechanism as is thought necessary to illustrate my invention, the moving parts being shown in one position, wherein the escape-wheel is stopped by the transfer-pallet point, the section being taken on line 1 in Fig. 3; Fig. 2, a similar view showing the moving parts in the second position, wherein the escape-wheel is stopped by the release-pallet point; and Fig. 3, a broken sectional view through the bearing-plates, showing my improved escapement mechanism in side elevation.

A is the escape-wheel of the watch-movement, and *a* its pinion journaled in the bearing-plates *xx'*. The escape-wheel is provided with the usual peripheral teeth, which may be of any desired form.

B is the balance-wheel, provided with the usual hair-spring, (not shown,) and *b* its staff, journaled in the bearing-plates *xx'*.

Fixed upon the balance-staff *b* is a roller C, comprising a disk in two steps of unequal diameter *c* and *d*. In the smaller step *c* is a peripheral recess *c'*, and in the periphery of the larger step *d* is a notch presenting an impact-shoulder *d'*. On the step *d* is an eccentric rack-engaging ruby-pin or roller-pin *d''* in radial line with the center of the recess *c'*. D is a balance-lever having the short coun-

terbalance-arm D', long arm D², and fulcrum-staff *e*, pivoted in the plates *xx'*. On the end of the arm is a head D³, presenting forks preferably formed with notches *f f' f²* and with intervening concave recesses *g g'*, adapted to fit loosely partly around the surface of the step *c* of the roller, as shown. Fixed to the staff *e* is a cylindrical rocker E, formed on one side with segmental recess E', at the opposite edges of which are stops or shoulders *h h'*.

F is an anchor or anchor-lever on a fulcrum-staff *i*, journaled in the plates *xx'*, the lever having the bent long arm F' and short arm F². At the end of the arm F² is a shoulder 65 or release pallet-point *k*, and on the arm F' in the position shown is a shoulder or transfer pallet-point *k'*. The free end of the anchor-lever is forked, as shown, to present the shoulders *l l'*, the end between the shoulders 70 being concave in an arc corresponding with the circumference of the rocker E.

Fig. 1 shows the balance-wheel on its impulse-stroke turning in the direction of the arrow just after the impact-shoulder *d'* has 75 been struck and released by the tooth *m* of the escape-wheel in the usual manner. The ruby-pin *d''* has just passed out of engagement with the notch *f'*, leaving the lever D in the position wherein the shoulder *h* engages the 80 shoulder *l* thereon to hold the transfer-pallet *k'* in the path of the tooth *m'* of the escape-wheel to stop the latter. I prefer to provide a balance-wheel having a long angular stroke 85 on account of the increased accuracy of its control upon the escapement mechanism thereby affected, and while it is usual in watch-movements to provide balance-wheel-operating mechanism which turns the balance-wheel normally but a half-revolution or 90 less, or at most a three-quarter revolution, in each direction I provide, for the reason stated, balance-wheel-operating mechanism which causes the balance-wheel to turn normally about a full revolution in each direction from 95 the point of impact with each impulse. In escapements as hitherto provided it has been considered unsafe to permit so great a normal stroke of the balance-wheel, because of the danger when the balance-wheel is given 100 an undue impulse, as when the watch is shaken, of the pallet's unlocking a second

time in a chronometer-watch or the jewel's striking an obstruction, such as the back of the lever in a lever-watch, and thus increasing the time by rebounding or breaking the jewel. In my improved construction these dangers are overcome. In its further movement on the impulse-stroke from the position shown in Fig. 1 the ruby-pin d^2 when it reaches the notch f will enter the latter and swing the lever on its fulcrum, turning the shoulder h farther beneath the shoulder l . This turning of the lever may continue under any undue influence against the balance-wheel until the notch f reaches the position of the notch f' in Fig. 1. In the return stroke of the balance-wheel the ruby-pin d^2 enters the socket f' and in turning in the direction indicated by the arrow in Fig. 2 moves the lever D from the position shown in Fig. 1 to that shown in Fig. 2. This movement of the lever D turns the shoulder h out of engagement with the shoulder l , thus releasing the anchor-lever and permitting it to be swung by pressure of the tooth m' against the pallet-point k' to release said tooth, the shoulder portion l moving in the recess E and the pallet-point k moving into the path of the escape-wheel tooth m^2 to engage and stop the same. This engagement causes the shoulder l' to be pressed against the shoulder h' . The base of the recess E' presents a convex impact-surface E^2 for the shoulders l l' to strike against, and thus prevent their passing the centerline of the rocker and becoming wedged. In the further turning of the balance-wheel from the position shown in Fig. 2 in the direction of the arrow in that figure the ruby-pin d^2 may enter the notch f^2 and under any undue influence against the balance-wheel swing the lever to the position wherein the said notch is in the position of the notch f' in Fig. 2, returning the lever in its reverse movement and releasing it at the position thereof shown, then reengaging the notch f' in its further movement and releasing said notch when the impact-face d' is struck by the next tooth m^3 of the escape-wheel. Thus it will be seen that the balance-wheel is free to turn approximately two full revolutions in each direction from the impulse-point, which is in excess of any ordinary requirements, even when the movement is violently shaken. The recesses g g' by their engagement with the step c of the roller prevent any displacement of the lever while the ruby-pin d^2 is out of engagement therewith.

My improved escapement employs comparatively few parts, all of which are of particularly simple, strong, and inexpensive construction. The anchor is simply a lock for the escape-wheel and does not operate against the balance-wheel, as in lever-watches. The pallet-points present inclined shoulders to the escape-wheel teeth to be moved by pressure thereof to swing the anchor when its shoulders are out of engagement with the

rocker. This construction reduces friction to a minimum. As the construction dispenses with the locking and other auxiliary springs incident to most other chronometer-escapements, its action is positive throughout and practically free from danger of unlocking when the balance-wheel makes more than one turn and of variations which would interfere with its accuracy. 75

While I prefer to construct my improvements throughout as shown and described, they may be variously modified in the matter of details of construction without departing from the spirit of my invention as defined by the claims. 80

What I claim as new, and desire to secure by Letters Patent, is—

1. In a chronometer-escapement, the combination with a toothed escape-wheel, and balance-wheel in the path thereof, of a fulcrumed anchor-lever provided with pallets, at opposite sides of its fulcrum, and with pallet-locking shoulders, a balance-lever having shoulders movable to engage and release said pallet-locking shoulders, forks on said lever and a ruby-pin on said balance-wheel. 85

2. In a chronometer-escapement, the combination with a toothed escape-wheel, and balance-wheel in the path thereof, of a fulcrumed anchor-lever provided with inclined pallets at opposite sides of its fulcrum to be moved by pressure against them of the escape-wheel teeth, and provided with pallet-locking shoulders, a balance-lever having shoulders movable to engage and release said pallet-locking shoulders, forks on said lever and a ruby-pin on said balance-wheel. 95

3. In a chronometer-escapement, the combination with the toothed escape-wheel and balance-wheel in the path thereof, of a fulcrumed anchor-lever provided with pallets, at opposite sides of its fulcrum, and with pallet-locking shoulders at one end, a fulcrumed balance-lever having shoulders movable to engage and release said pallet-locking shoulders, forks on said lever and a ruby-pin on said balance-wheel. 105

4. In a chronometer-escapement, the combination with the toothed escape-wheel and balance-wheel in the path thereof, of a fulcrumed balance-lever, a rocker on said lever near its fulcrum, having pallet-locking shoulders and a recess between said shoulders, an anchor fulcrumed between its ends, having pallets on opposite sides of its fulcrum, and a recess at one end, fitting slidingly against said rocker, flanked by pallet-locking shoulders adapted to enter the said recess in, and engage the shoulders on, said rocker in their movement, forks on said balance-lever, and a ruby-pin on said balance-wheel, substantially as and for the purpose set forth. 115

5. In a chronometer-escapement, the combination with the toothed escape-wheel and balance-wheel in the path thereof, of a fulcrumed balance-lever, a rocker on said lever

near its fulcrum, having pallet-locking shoulders and a recess between said shoulders, an anchor fulcrumed between its ends, having pallets on opposite sides of its fulcrum, and 5 a recess at one end, fitting slidingly against said rocker, flanked by pallet-locking shoulders adapted to enter the said recess in, and engage the shoulders on, said rocker in their movement, an impact-surface in said recess 10 for the said pallet-locking shoulders to strike against, forks on said balance-lever, and a ruby-pin on said balance-wheel, substantially as and for the purpose set forth.

6. In a chronometer-escapement, the combination with the toothed escape-wheel and balance-wheel in the path thereof, of a fulcrumed anchor provided with pallets at opposite sides of its fulcrum and with pallet-locking shoulders, a balance-lever having 15 shoulders and movable to engage and release therewith said pallet-locking shoulders, forks on said lever presenting three ruby-pin-en-

20

gaging notches, and a ruby-pin on said balance-wheel, substantially as and for the purpose set forth.

25

7. In a chronometer-escapement, the combination with an escape-wheel and balance-wheel, of a fulcrumed anchor provided with pallets at opposite sides of its fulcrum, and with pallet-locking shoulders, a balance-lever 30 having shoulders and movable to engage and release therewith said pallet-locking shoulders, a roller on the balance-wheel provided with an impact-face, in the path of the escape-wheel, and with a ruby-pin, and forks on said 35 lever presenting three engaging notches for the said ruby-pin with intermediate engaging recesses for said roller, substantially as and for the purpose set forth.

JOHN W. NUNAMAKER.

In presence of—

WALTER WINBERG,
WM. B. DAVIES.
